[57] CLAIM

The ornamental design for a toy desk, as shown and described.

DESCRIPTION

FIG. 1 is a front, side and top perspective view of a toy desk showing my new design;

FIG. 2 is a front perspective view, the rear being identical thereto except for the cord on the moveable desk top and the tradename logo;

FIG. 3 is a side perspective view, the opposite side being a mirror image thereof;

FIG. 4 is a top plan view thereof;

FIG. 5 is a front perspective with the drawers in extended position;

FIG. 6 is a front perspective with the top in raised position;

FIG. 7 is a rear perspective view thereof; and,

FIG. 8 is a rear perspective view with the top in an alternate position of use.
